UNITED STATES PATENT OFFICE.

JOHN N. KILLOUGH, OF AURORA, TEXAS.

MACHINE FOR STRETCHING AND REMOVING FENCE-WIRES.

SPECIFICATION forming part of Letters Patent No. 291,743, dated January 8, 1884.

Application filed July 25, 1883. (No model.)

To all whom it may concern:

Be it known that I, JOHN N. KILLOUGH, of Aurora, in the county of Wise and State of Texas, have invented a new and Improved Machine for Stretching and Removing Fence-Wires, of which the following is a full, clear, and exact description.

The object of my invention is to provide a simple, effective, and inexpensive machine for stretching the wires of fences along the fence-posts, and straining the wires taut while they are being fastened to the posts, and also for removing the wires from the posts when required, as in removing or resetting a fence.

Reference is to be had to the accompanying drawings, forming part of this specification, in which similar letters of reference indicate corresponding parts in all the figures.

Figure 1 is a partly broken side elevation of my improvement as applied to use. Fig. 2 is a rear view, and Fig. 3 is a front view, thereof. Fig. 4 is a detail sectional view of the windlass and its ratchet-and-pawl device, and Fig. 5 is a perspective view of one of the wire-spools.

I make the base or support for the machine in the form of a sled, consisting of side runners, *a*, and end cross-pieces, *b*, and by preference I lay a floor, *c*, between these runners and cross-pieces, to serve as a carrier-platform for tools used about the machine, or for the spools of wire in laying a long stretch of fence.

The letter *d* represents side frames, consisting, preferably, of two inclined bars or planks, *d* *d'*, suitably fastened to each other at the top, and to the runners at their lower ends, and stayed above the sled by the cross-bar *e*. In notches *f* of side frames, *d*, which notches are open, preferably, from the under side of the frames, and extend along about centrally of the width of the frame-bars, suitably for bearings, I support the shafts *g*, each adapted to receive two coils or spools, *h*, of barbed or other fence-wires *i*, the spools of wire being supported so that as the sled is drawn forward along the fence-posts *j* the wires *i* will be paid out or off from the spools *h*, so as to provide a four-wire fence, as in Fig. 1; or the number and arrangement of the spools *h* may vary to lay one, two, or three wires along the posts, as the height and style of the fence may require.

I make the spools *h*, as in Fig. 5, with ends of crossed pieces *h'*, connected at the angles by bars or strips *h''*, on which the wire is wound, one or both ends *h'* being grooved or splined at *h'''* to receive a key, *h'''*, as in Fig. 3, which key also enters a groove in the spool-shaft for locking the spools to the shafts to rotate therewith.

To prevent undue slackness of the wires *i* when first paid off from spools *h*, I fit the shafts *g* of the spools with a friction-brake device, consisting, as shown, of a pair of jaws, *k*, pivoted together and to the frame *d* at *l*, and having the screw *m* fitted at their free ends, so that when the jaws *k* are clamped on opposite sides of the shafts *g*—and preferably inside of heads formed on the ends of the shafts—by the action of the screw *m*, the spools will revolve to pay out the wires *i* only when the sled is drawn forward, thereby partially straining the fence-wires by the advance of the machine.

In the front frame-bars, *d'*, I arrange the windlass *n*, which has lever-arms *o*, by which to turn it forcibly when the wires *i*, after being paid off from the spools *h*, are connected, one at a time, to the barrel portion *n'* of the windlass, from which arms *o* project. The windlass has fixed to it the ratchet *p*, which is engaged by a pawl, *q*, pivoted to frame *d* to prevent back-slip of the strained wires prior to their secure fastening to the fence-posts by staples *r* or other suitable means. The portion *n''* of the windlass *n* is adapted to receive an empty wire-spool, *h*, on which loosened fence-wires may be wound by turning the crank *s* of the windlass when removing a wire fence, the machine in this case being drawn wholly or partly by the tension of the winding wire.

The operation is as follows: The posts *j* being set, and the spools *h* adjusted to the sled, and the wires *i* secured to the end post, the machine is drawn along the fence-posts by horse or other power applied at the draft-connection *t*, and when the wires *i* have been fully paid off the spools *h* the wires are suitably connected to windlass *n* and strained taut by working lever-handles *o*, when the wires are secured to the posts by staples or otherwise, as desired. Stakes may be driven into

the ground behind the sled, to hold it from moving back when straining up the wires. In removing a wire fence the operation is expeditiously and conveniently performed by 5 winding the loosened wires on the spool *h*, fixed to windlass *n*, as above described.

The details of construction may vary within the scope of my invention—as, for instance, the clamp-bars *k* may be fitted with a screw, 10 *m*, at both ends, if desired, and the bearings for the spools in the frame may consist of suitable metallic sockets fixed to the frame *d*; but the construction shown is at present preferred.

It is believed that my improved machine 5 has material advantages as regards economy of time and labor in the construction, adjustment, and removal of wire fences of all descriptions, and the machine may be cheaply made, and is well calculated for durability in 10 use.

I am aware that fence-wire stretchers have

been used on wheels and runners, and that they have been provided with windlasses, braces, spindles, reels, standards, stretcher-bars, and levers; but

25

What I claim as new is—

1. In a machine for stretching and removing fence-wires, the combination of the sled *a* *b*, frame *d* *e*, spool-carrying shafts *g*, brake device *k l m*, windlass *n*, carrying lever-arms 30 *o*, spool *h*, crank *s*, ratchet *p*, and pawl *q*, substantially as shown and described.

2. The combination, with the shaft *g*, spools *h*, and frame *d*, of the jaws *k*, pivoted together, pivoted to the frame at *l*, and provided with 35 the screw *m* at their free ends, as and for the purpose specified.

JOHN N. KILLOUGH.
